UNITED STATES PATENT OFFICE.

OTTO W. SCHAUM, OF PHILADELPHIA, PENNSYLVANIA.

DESIGN FOR A SIDE FRAME FOR SHEDDING MECHANISMS.

SPECIFICATION forming part of Design No. 33,831, dated January 1, 1901.

Application filed December 6, 1900. Serial No. 38,963. Term of patent 14 years.

To all whom it may concern:

Be it known that I, OTTO W. SCHAUM, a citizen of the United States, residing in Philadelphia, in the county of Philadelphia and State of Pennsylvania, have invented a new and useful Design for a Side Frame for a Shredding Mechanism; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to the accompanying drawings, wherein corresponding letters of reference indicate like parts, Figure 1 is a side view of a shredding-mechanism side frame constructed in accordance with my invention. Fig. 2 is a top plan view thereof; and Figs. 3, 4, and 5 are sectional views, respectively taken on the lines $x-x$, $y-y$, and $z-z$ in Fig. 1.

As essential features of design the shredding-mechanism side frame which is the subject of the said design comprehends in its construction a substantially rectangular body portion and an elongated arm portion, the latter having elongated openings disposed the one obliquely relatively to the other.

a designates the substantially rectangular body portion, and b the arm portion, extending from one of the upper corners of said body portion. At the upper corner adjacent said

arm portion and also at its diametrically opposite corner said rectangular portion has a boss $c-d$. Its lower side e is formed with a vertical guide f , which extends somewhat downwardly therefrom. The arm portion b has two elongated openings $g-h$, already referred to, whose direction of extension is substantially that of the arm portion itself. One of these openings, the opening g , is disposed obliquely with reference to the other. From the under side of the arm portion b depends an integral tapered projection j , having a boss k . A similar boss l is formed in said arm portion at one side of the base of said arm. The several bosses are penetrated by bearing-orifices m .

The surrounding edges of the side frame itself, as also of the guide f and openings g and h , are reinforced by flanges or ribs n on both sides of said side frame.

Having thus fully described my invention, what I claim as new, and desire to secure by Letters Patent, is—

The design for a side frame for a shredding mechanism substantially as herein shown and described.

In testimony that I claim the foregoing I have hereunto set my hand this 22d day of November, 1900.

OTTO W. SCHAUM.
